UNITED STATES PATENT OFFICE.

ALBERT E. DAVIS AND SIMON DAVIS, OF KEW GARDENS, NEW YORK.

DISPLAY DEVICE.

Application, filed December 26, 1924. Serial No. 758,013.

To all whom it may concern:

Be it known that we, ALBERT E. DAVIS and SIMON DAVIS, citizens of the United States, and residents of Kew Gardens, Queens 5 County, State of New York, have invented certain new and useful Improvements in Display Devices, set forth in the following specification.

This invention relates to display devices. 10 The object of the invention is to make possible the easy transportation of renewal displays sent out from a central source of distribution and their subsequent display in an advertising locality. To this end, there 15 is contemplated the employment of a flimsy sheet of material such as paper, cloth or the like, which has no inherent strength to maintain itself as a flat placard but which has considerable strength in tension and 20 in edgewise shear. The means contemplated for cooperation with such a sheet is a knock-down frame of simple, cheap construction which may be quickly jointed together to display the advertising and which, when 25 not in use, will occupy little space. It is contemplated that such a frame may be fabricated so cheaply as, for example, from bars or strips of wood, that one of the bars may be secured permanently to one edge of 30 a display strip about which bar the display strip may be rolled, the bar to serve as a stiffening member to protect against injuries during transportation and to be thrown away when a new sheet is to be 35 shown.

The above and further objects will be pointed out more in detail in the following 40 claims and will be understood by reference to the illustrative embodiment described in the following specification in connection with the accompanying drawings, which form a part hereof.

In the drawings—

Fig. 1 is a perspective view of one embodiment of the invention;

Fig. 2 is a section taking through the plane of line II—II of Fig. 1;

Fig. 3 is a perspective view, with parts broken away, of the renewable display 50 means; and

Fig. 4 is a fractional view corresponding to Fig. 1 showing a modification.

A reinforcing frame A is formed preferably of four wooden strips or bars, two extensors 1 and 2, adapted to lie when in use horizontally one above the other, and two 55

struts 3 and 4 adapted to extend upright to space the bars 1 and 2 apart. The ends of the bars are fitted with suitable connections such as the tongue and groove connections 5 and 6 which frictionally mutually engage to hold the frame A loosely assembled so as to have considerable strength against warping. In this construction all the outer faces 7 of the bars going to make up the frame are in substantially the same plane. A display sheet B preferably rectangular and of a size to accord with the frame A may be attached to one of the extensors, as for example, preferably to the top extensor. This may be accomplished by pasting the margin 8 directly to the outer surface of the bar or, if preferred, after the strip is pasted, as indicated in Fig. 2, the entire bar may be rotated clockwise 75 180° so that this end of the sheet B smoothly folds over the bar, and extends downwardly. The opposite edge 9 of the sheet B is brought under the bar 2 and up on the other side thereof, forming a fold. Suitable means is provided for exerting tension upon this edge 9.

In Fig. 1 the pair of tension springs 11 and 12, suitably secured as by screws 10 to the struts 3 and 4, may be provided with hooks 13 and 14 taking into eyelets 15 and 16 provided for that purpose in the edge 9. In this manner a spreading tension is provided for the edge 9 which is drawn towards the opposite extensor bar 1 stretching 90 the body of the sheet across the surfaces 7.

When large sheets are employed, it may be preferable to provide an additional member for the frame A in the form of an intermediate extensor a which has knock-down connection with the struts 3 and 4 through the medium of tongue and slot joints 17 and 18. In this modification, hooks 19 may be provided intermediate the struts 3 and 4 to cooperate with additional eyelets 20 through the medium of a lacing 21 of any suitable flexible material such as elastic or twine, it having been found that twine is sufficiently elastic for the purpose. In the modification of Fig. 4, spring tensors 11 and 12 are shown embodied, although for some purposes either the one or the other, the spring tensors 11 or the lacing 21 or both may be employed.

The use and functioning of the device is to supply renewal sheets preferably in the

form shown in Fig. 3, already pasted along one edge to an extensor 1 and which may be rolled up about the extensor 1 for mailing to the customer. To put the sheet in use, all that is necessary is to assemble it as shown in Fig. 1. The tension means pulling the sheet causes the strength of the sheet against buckling shear to combine with the resistance against compression of the struts 3 and 4, so that a stiff, flat placard is produced. The side edges 31 and 32 are free from the frame A. This freedom for the edges 31 and 32 is important together with the movability of the frame in its joints. As a result the frame adapts itself to the sheet shifting slightly in its own plane to produce a flat tensed display almost automatically. As a matter of fact, the entire structure is not complete as a placard until the flimsy sheet is caused to combine with the knock-down frame by the application of tension. In this respect, it is important to understand that all the expense usually entailed in the production of a stiff, rigid self-sustaining frame is done away with.

In addition to this advantageous saving in the cost of the frame itself, it should be borne in mind that the difficulty of transporting, as through the mail, a stiff placard is great, whereas the transportation of a sheet of paper rolled up on a wooden stiffener is the most feasible method for mailing.

The inventive thought may have a variety of expressions, as is contemplated in what we claim and desire to secure by United States Letters Patent:

1. In a display device in combination, a pair of extensor members adapted to be arranged in vertically spaced horizontal positions; a pair of struts; means for discon-

nectably framing said extensors and struts into substantially rectangular formation; a sheet of flimsy display material permanently secured at one edge to one of said extensor members and adapted to be rolled up thereon for transportation; and means for tensing a fold at the opposite ends of said sheet about the other of said extensor members. 45

2. In a display device in combination, a flexible sheet of paper; a knock-down frame comprising a plurality of bars having mating end connections adapted to be framed together to resist warping movements but free for some movement in the plane of said bars; a sheet of paper secured along one edge to one of said bars; and means for pulling a fold of said sheet under constant tension about an opposite bar, whereby said frame and said sheet mutually adapt themselves one to the other and the strength of said sheet in shear when under tension is combined with the compression and anti-warping resistance of said frame to form a flat self-sustaining display placard. 50 55

3. A display device comprising four 60 wooden bars having tongue and groove joints at their ends to form a knock-down rectangular frame, one surface of which is located in substantially the same plane; a paper display sheet attached to one of said bars and adapted to be drawn over an opposite bar in the form of a fold; and means for drawing the folded over edge of said fold towards the opposite bar so as to combine the cooperating tension, shear and compression qualities of said parts to produce a flat, strong display placard. 70 75
